UNITED STATES PATENT OFFICE.

GEORGE CODE AND HANS KNUDSEN, OF BOSTON, MASSACHUSETTS, AS-SIGNORS TO THE LIQUID AIR, POWER AND AUTOMOBILE COMPANY, OF WEST VIRGINIA.

ADJUSTABLE PULLEY-GEAR.

SPECIFICATION forming part of Letters Patent No. 652,384, dated June 26, 1900.

Application filed September 7, 1899. Serial No. 729,683. (No model.)

To all whom it may concern:

Be it known that we, GEORGE CODE, a subject of the Queen of Great Britain, and HANS KNUDSEN, a citizen of the United States, residents of Boston, in the county of Suffolk and State of Massachusetts, have invented certain new and useful Improvements in Adjustable Pulley-Gears, of which the following is a specification.

- 10 Our invention relates to improvements in adjustable pulley-gears; and the invention consists in the peculiar construction and arrangements of parts, as hereinafter described, and pointed out in the claims.
- 15 Referring to the accompanying drawings, Figure 1 represents a plan or top view of an apparatus embodying our invention, showing one of the rigid sliding cones drawn back and the other rigid sliding cone pushed in and the 20 fixed expandible cones in their relative positions. Fig. 2 is a similar view showing the rigid sliding cones in a central position and the adjustable cones in their relative positions. Fig. 3 is a section through one of the 25 sliding rigid cones and one of the adjustable cones, the sliding cone being drawn out. Fig. 4 is an outer end view of one of the adjustable cones. Fig. 5 is an outer end view of one of the rigid sliding cones.
- 30 A represents the supporting-frame. To this frame are secured bearings B B. C C' are shafts mounted in said bearings, each of said shafts having at one end a disk secured thereto by brazing, riveting, or other means. Each of 35 said disks D is formed with a number of ribs, the disk being furcated at the end of each rib. In each of said forks is fulcrumed an arm or lever E. To the upper end of each of said arms or levers is attached one end of a spring F, the 40 other end of said spring being secured to the hub of the disk D, as shown. The outer end of each of the arms or levers E is fitted with a pivoted shoe G to receive the belt H, thus forming what we term the "fixed expandible cone." The shoes G are each formed with a rearward extension g, having an opening, through which a bar or arm of the rigid sliding cone passes, as hereinafter described. Upon each of said shafts C C' is also mounted, 45 but so as to slide freely, what we term a "rigid

sliding cone," consisting of a small inner disk I and an outer disk I', connected together by arms or bars I². The outer portions of the disks I' are each formed with a hub having a recess i formed therein, in which the forked 55 ends of a shipper-lever J fits, said shipper-lever being fulcrumed in its center at a to a cross-bar A' in the center of the frame A. In order to impart a sliding motion to the hub of the disk I' and to the shipper-lever J for 60 operating the arms of the expandible cones, we employ a lever K, furcated at one end to fit into the groove i in the hub of the disk I' on the shaft C', the outer end of said lever being formed with an internal screw-thread 65 that works upon a screw-threaded rod L, mounted in bearings B', attached to the frame A, the outer end of said rod L being fitted with a grooved pulley M, operated by a belt, as shown, or other suitable means, whereby 70 the lever K is caused to travel upon the screw-thread rod L and imparts a traveling motion to the hub of disk I' and through shipper-lever J a similar motion, but in an opposite direction, to the hub of the disk I', so that 75 when one of said disks is forced in the other will be forced out, and vice versa. Each of the arms of the rigid cones passes through a slot formed in the interior g at the rear of the 80 shoes G on the ends of the arms of the expandible cones. Motion is transmitted to the shaft C from any suitable source, and motion is transmitted from the shaft C' by gears or other means to the machine to be driven.

The operation is as follows: Motion is first 85 transmitted to the driving-shaft C from any suitable source by means of a belt. A band passing over the pivoted shoes on the fixed expandible cones imparts motion to the driven shaft C'. Thus if the shipper-lever is parallel 90 both shafts will be rotated at the same speed; but if the shipper-lever is shifted by means of the lever K one of the rigid sliding cones will be drawn out and the other forced in and thus alter the diameter of the ends of 95 the expandible cones, so that the speed will be altered as required.

What we claim is—

1. An adjustable pulley-gear comprising two parallel shafts, each having mounted 100

thereon a fixed expandible cone, and a rigid slidable cone working within same, a shipper-lever for holding the rigid slidable cones in position, and mechanism for shifting one of the 5 hubs of sliding cones; substantially as set forth.

2. An adjustable pulley-gear having two parallel shafts, a fixed expandible cone and a rigid slidable cone on each shaft, a shaft having 10 a worm thereon, a lever having an internal worm at one end to work upon same and a fork at the other end to embrace the boss of one of the slidable cones, and a shipper-lever for imparting a relative movement to the 15 other slidable cone; substantially as set forth.

3. In an adjustable pulley-gear, having two parallel shafts, a fixed expandible cone and a rigid slidable cone upon each shaft, a shoe pivoted at the end of each of the arms or levers 20 of the expandible cones for carrying a belt or cord for imparting motion from the

driving-shaft to the driven shaft, in combination with a shipper-lever, and a lever for imparting motion to one of the slidable cones, substantially as set forth.

25

4. In an adjustable pulley-gear, a rigid expandible cone, consisting of a disk secured to the shaft, a number of arms or levers attached to the periphery of said disk, springs connected to the outer ends of said levers and to 30 the hub of the disks, and shoes at the inner ends of said arms or levers for carrying a band, in combination with rigid slidable cones; substantially as and for the purpose set forth.

In testimony whereof we have affixed our 35 signatures in presence of two witnesses.

GEORGE CODE.
HANS KNUDSEN.
